FIG. 1 is a front perspective view of a light-emitting diode, showing our new design;

FIG. 2 is a rear perspective view thereof;

FIG. 3 is a front elevational view thereof;

FIG. 4 is a rear elevational view thereof;

FIG. 5 is a bottom plan view thereof; the opposite side being a mirror image thereof; and,

FIG. 6 is a right side elevational view thereof; the opposite side being a mirror image thereof.
